GOLF BALL HOLDER

Filed May 18, 1928

WITNESS: *Frank D. FreDETTE*

UNITED STATES PATENT OFFICE.

FRANK D. FREDETTE, OF BROOKLYN, NEW YORK.

GOLF-BALL HOLDER.

Application filed May 18, 1928. Serial No. 278,819.

This invention relates to improvements in golf ball holders.

The primary object of the invention resides in a golf ball holder for mounting upon a 5 golf bag, within which a supply of golf balls may be conveniently carried for use when needed, and which is designed to eliminate the usual ball pocket provided on the bag which has not proven highly satisfactory from the 10 view point of the golfer.

Another object is to provide a golf ball holder adapted to contain a supply of golf balls in stack formation, and by which the same may be successively dispensed by the 15 manual actuation of a turnable knob.

Another object is the provision of an attachment for golf bags which includes a holder closed at one end by an openable cover, while a carrier is vertically slidable within the holder 20 and on which the balls are supported in stack formation, the carrier being movable by the manual actuation of a rotatable screw, which lifts the stack of balls vertically to a position where the uppermost ball may be 25 conveniently removed after the opening of the cover.

With these and other objects in view, the invention resides in certain novel construction and combination and arrangement of 30 parts, the essential features of which are hereinafter fully described, are particularly pointed out in the appended claims, and are illustrated in the accompanying drawing, in which:—

35 Figure 1 is a perspective view of a golf bag with my improved golf ball holder mounted thereon.

Figure 2 is an enlarged side elevation of the golf ball holder.

40 Figure 3 is a fragmentary top plan view of a golf bag equipped with my golf ball holder.

Figure 4 is an enlarged fragmentary vertical sectional view on the line 4—4 of Figure 3.

Figure 5 is a horizontal sectional view on the line 5—5 of Figure 4.

Figure 6 is a detail perspective view of the top of the holder with the cover in an open position and with the manipulating knob removed.

Figure 7 is a detail perspective view of the carrier member per se.

55 Referring to the drawings by reference characters, the numeral 10 designates a golf bag of any well-known construction in which

the golf sticks of a golfer are carried, and within which my improved golf ball holder 11 is securely mounted to the side wall by fastening means 12. The top of the holder is 60 flush with the open top of the golf bag, while a strap 13 bridging the open end of the bag serves to keep the "iron golf sticks" from the "wood golf sticks", the wood sticks being carried on that side of the strap on which the 65 holder is disposed.

The golf ball holder 11 comprises an elongated casing 14 closed at its bottom end and open at its top, while the interior of the casing is formed to provide a ball compartment 15 70 and an offset tubular portion 16, communicating with the ball compartment, through a slot 17. The cross sectional diameter of the ball compartment is such as to freely receive a standard size golf ball.

75 The open end of the casing is closed by an openable hinged cover 18, held in a closed locked position by a headed stud 19 turnably mounted in the top of the casing. The cover has a slot 20 therein for the passage of the 80 head of the stud, when the stud is aligned therewith, after which the stud is turned to dispose the head at right angle to the slot to lock the cover against accidental swinging movement.

85 Journalled in the opposed end walls of the offset portion 16 is a rotatable screw 21, one end of which extends beyond the top of the casing to fixedly receive a manipulating knob 22. The top of the casing surrounding the 90 screw shaft is provided with a boss having ratchet teeth 23 thereon for coaction with teeth 24 on the underside of the manipulating head. The screw shaft is mounted for a slight longitudinal movement to allow the teeth on the manipulating head to ride over the ratchet teeth 23 upon turning of the shaft in a clockwise direction, and for facilitating counter-clockwise turning by the operator lifting up on the shaft and turning the same. The 95 ratchet teeth serve to lock the shaft in a set position against accidental turning in one direction.

Movable longitudinally within the casing 105 is a carrier member 25 including a disk portion 26 disposed within the ball compartment 15 and having a concave seat 27 for the lowermost of a plurality of golf balls 28 arranged in stack formation, one upon the other. A head 29 is formed integral with a reduced 110 neck 30 extending from the disk 26 and is disposed for sliding movement in the tubular

portion 16, while the reduced neck is slidable between the walls of the slot 17 which guides the carrier member in its vertical movements and serves to prevent any turning movement of the member within the casing. The head is provided with a threaded opening 31 which co-acts with the screw shaft 21, whereby turning of the shaft will impart sliding movement to the carrier member.

10 In practice, a supply of golf balls 28 are placed within the ball compartment 15 in stack formation, it being understood that the cover 18 is in an open position. When a player wishes to remove one or more of the 15 golf balls, he opens the cover and proceeds to turn the knob 22 in a counterclockwise direction. The screw shaft 21 during rotation imparts a vertical sliding movement to the carrier member 25, which lifts the stack 20 of balls until the uppermost ball is disposed above the top of the casing whereupon it may be removed by the hand of an operator. The weight of the carrier member and balls might tend to cause the carrier member to drop when 25 the manipulating head is released by an operator, but this is prevented by the ratchet mechanism hereinbefore mentioned. The next uppermost ball may be dispensed upon only a limited turning of the screw shaft.

30 Although I have shown the ball holder mounted within a golf bag, it will be appreciated that it can also be mounted exteriorly of the same if desired.

While I have described what I deem to be 35 the most desirable embodiment of my invention, it is obvious that many of the details may be varied without in any way departing

from the spirit of my invention, and I therefore do not limit myself to the exact details of construction herein set forth nor to anything less than the whole of my invention limited only by the appended claims. 40

What is claimed as new is:

1. A golf ball holder comprising a casing open at one end and adapted to contain a supply of golf balls, and manually operated means operable from the top of said casing for lifting the supply of golf balls toward the open end thereof, said manually operated means including a member slidable within said casing, and a rotatable screw shaft to which said member is threadedly connected, and co-acting ratchet teeth between said rotatable screw shaft and the top of said casing for locking said screw shaft against accidental turning movement in one direction. 45

2. A golf ball holder comprising a casing having a golf ball compartment therein, an openable door at one end of said compartment, a screw shaft journaled in said casing, and extending beyond the top thereof, a manipulating head on the extending end of said screw shaft, and a carrier member slidable within said ball compartment and threadedly mounted on said screw shaft, and means for locking said screw shaft against accidental turning movement in one direction, said means including coacting ratchet teeth between said manipulating head and the top of said casing. 50

In testimony whereof I have affixed my signature.

FRANK D. FREDETTE.
